AUTOMOBILE FLOOR MAT

Harlan L. Lea, P.O. Box 274, Wapakoneta, Ohio

Filed Mar. 16, 1964, Ser. No. 79,002

Term of patent 14 years

(Cl. D9—6)

FIG. 1-

FIG. 5-

FIG. 1 is a front view in perspective showing an automobile floor mat embodying my new design;

FIG. 2 is a plan view of the mat shown in FIG. 1 and shown on an enlarged scale;

FIG. 3 is a side view in elevation of the mat;

FIG. 4 is a front end view in elevation of the mat; and

FIG. 5 is a rear end view in elevation of the mat.

I claim:

The ornamental design for an automobile floor mat, as shown.
